STOCKING

John P. Mitzel, Derita, N. C., assignor to Larkwood Silk Hosiery Mills, Inc., Charlotte, N. C., a corporation of North Carolina

Application February 10, 1941, Serial No. 378,144

6 Claims. (Cl. 66—182)

This invention relates to an improvement in sheer hosiery and more especially to a novel heel construction employing reinforced areas at the junction point of the foot portion and the heel tabs, and in wales of the leg portion adjacent to the heel portion where the wales are topped for knitting the foot portion.

It is a well known fact that one of the most critical areas in a ladies' full fashioned stocking is along the line where the leg portion is united at the foot portion. A majority of hosiery manufacturers employ two machines during manufacture, namely, a machine called a legger and a machine called a footer. The leg portion, including the heel tabs, is knitted upon the legger and then certain loops on the leg portion and heel tabs are topped onto the footer bar and then transferred to the footer for knitting the foot portion. The topping operation is performed manually and very often some of the threads forming the loops are split by the points on the footer bar, resulting in only a part of the thread at this point being knit with the first course on the footer. This results in a very weak wale. Due to the general construction of the hosiery, the loops at the heel corner have a greater strain thereon during wear than the other loops. Therefore, it is necessary to have added reinforcement at the heel corners.

Another difficulty heretofore encountered, even where the topping was perfectly performed, has been the overcoming of the added stress at the heel corners created as a result of the wales at the heel corners changing their direction. In a conventional full fashioned stocking, the wales extend almost vertically downwardly until the lower heel tabs are reached and then the wales extend in a substantially horizontal direction throughout the foot portion. Since the instep of the wearer tends to stretch the stocking a greater amount at the upper portion of the lower heel tabs there is a resulting increased stress at the heel corners which should be taken into consideration in fabric construction.

It is an object of this invention to provide a stocking devoid of the reinforced heel and having a reinforced area at the junction of the heel tabs, the foot portion and the leg portion of the stocking so that the stresses at these points will not break the loops and cause runs. Such a construction reinforces one of the most critical points, leaving other portions not subjected to greater stresses, to be made of light weight sheer material.

Some of the objects of the invention having

been stated, other objects will appear as the description proceeds, when taken in connection with the accompanying drawing, in which—

Figure 1 is a view of a completed stocking embodying the present invention;

Figure 2 is a view of the lower portion of the leg of the stocking shown in Figure 1, prior to the same being attached to the foot portion, and subsequently looped and seamed;

Figure 3 is a view similar to Figure 2 but showing the foot portion knitted onto the lower end of the leg portion;

Figure 4 is a sectional view taken along the line 4—4 in Figure 3;

Figure 5 is a sectional view taken along the line 5—5 in Figure 3.

Referring more particularly to the drawing, the numeral 10 broadly designates a full fashioned stocking having a welt portion 11, shadow welt portion 12 and leg portion 13. The leg portion 13 has knitted integral with the lower portion thereof, suitable spaced non-reinforced heel tabs 15, the lower ends of which are narrowed as at 16 to give the proper shape to the heel after the stocking is seamed and looped along the edges 17 and 29, respectively. Upon the completion of the leg portion, using double construction, the loops along dotted lines 19 and 27 are topped upon a suitable footer bar and are transferred to a machine called a footer. The excess portion 19a which is disposed below the topping line 19 is ravelled or otherwise removed from the footer bar so that the bare loops of the course indicated by dotted line 19 will be knitted with the foot portion 20. At the same time, the knitting from dotted lines 27 is carried out.

It is a well known fact that the most critical points in the construction of a full fashioned stocking are the points which are located at the junction of the heel tabs and the leg portion of the stocking and the heel portion commonly known as the heel corners. These points are designated by the reference characters 24 in Figures 2 and 3. In order to reinforce the wales

and courses of a sheer stocking at these points to prevent runs from occurring, suitable reinforced areas are provided in leg portion 13, said wales being designated by reference characters 38, 39, 40, 41, 42 and 43, and each of said areas

being designated by the reference character 36. Any desired number of reinforced wales and courses may be provided, and this invention is not limited to the number shown in the drawing. Four of the reinforced wales namely 40, 41, 42 and 43 extend downwardly along each of

the proximate edges of the heel tabs 15 and throughout the length thereof forming portions 35. The remaining portions of the heel tabs except as indicated in the drawing are not reinforced. The two adjacent reinforced wales 38 and 39 begin substantially at the same points in the leg portion as the other reinforced wales and extend downwardly through the topping line 19 and through excess portion 19a. If desired, the bottom portion of the reinforced strips 35 may be widened as at 26 to cover the entire width of the heel tabs. During a transfer operation, the points of the footer bar are also inserted along topping lines 27 of the reinforced strips 35 of the heel tabs as well as along topping line 19, thereby causing the points on the footer bar to penetrate both edges of the two heel tabs and the instep of the leg portion along topping lines 19. Lines 27 are usually loose wales caused by a boning operation.

In the present embodiment of the invention, the lines 27 are disposed upon the third wale from the edge of the heel tabs and between wales 42 and 43 (Figure 5). It is to be understood however, that the topping lines 27 can be located along any desired wale in the reinforced portions 35. After the foot portion has been knitted onto the leg portion, the stocking assumes the position as shown in Figure 3 after which the ends of the heel tabs are placed upon looper points along lines 29 and then the excess portion 29a is ravelled or otherwise removed so that the bare loops of the looper points will unite the tabs. The other portions of the stocking are seamed as at 17, as previously described.

It will be noted that the reinforced areas 36 appear in the leg portion 13 of the completed stocking. When these reinforced areas reach the heel tabs and merge into portions 35 only one course namely 43 of each reinforced area is interknitted in the body of the stocking so as to be visible from the exterior. This visible reinforced area formed by wale 43 is designated by the reference character 35a. The remainder of the reinforced strip 35 is not knitted into the body of the stocking but instead is floated on the inside of the stocking forming a loose flap 35b attached only along line 27. In other words, single strand loops are employed in the stocking at all areas except areas 35a and 36 and 26, where multiple strands loops are used. If desired toe portion 30 can be reinforced.

By employing this type of construction, it is seen that a sheer stocking is produced and having the critical points 24 reinforced so that the increased stresses will be taken care of to eliminate runs in the stocking. The narrow reinforced strips 35a along the junction lines between the heel tabs and the foot portion gives an added reinforcement which supplements the reinforced area 36 to distribute the stresses exerted upon the area 36 throughout the heel.

In the drawing and specification there has been set forth a preferred embodiment of the invention, and although specific terms are employed, they are used in a generic and descriptive sense only and not for purposes of limitation, the scope of the invention being set forth in the appended claims.

I claim:

1. A stocking comprising a leg portion, heel tabs, integrally knitted to the leg portion and being of the same weight fabric as the leg portion for a substantial portion of their length and having the lower tip portions of said heel por-

tions reinforced, a foot portion joined to the leg portion and to one edge of each heel tab, a reinforced area in the leg portion at each of the junction points between the leg, the heel tab and the foot portion, and a second narrow reinforced area disposed along one edge of each tab adjacent the junction line between said tab and said foot portion.

2. A stocking comprising a leg portion having 10 a major portion thereof knitted from a single thread, heel portions each having a major portion thereof knitted from a single thread and a foot portion knitted from a single thread down to its toe portion, the leg portion, the heel portions and the foot portion meeting at points on 15 opposite sides of the stocking, the leg portion having a pair of reinforced areas disposed immediately above the end of the loose course in the leg portion forming the topping line between the leg and foot portion, said reinforced areas also extending along proximate edges of the heel portions and including the loose wales employed as a topping line whereby the reinforced wales in the edges will be disposed on the inside of the stocking 20 as loose flaps.

3. A stocking comprising a leg portion, heel tabs, a foot portion and a toe portion knitted from a single strand throughout the leg portion, heel tabs and foot portion down to the beginning 30 of the toe portion, excepting a few courses beginning of the toe portion, excepting a few wales in the leg portion near the junction point of the heel tabs and the leg portion, and a few wales from the inner edges of the heel tabs and the tips of the heel tabs, some of said reinforced wales in the leg portion extending below the topping line in the leg portion, so that when the leg portion and heel tabs are topped in the reinforced areas, the reinforced wales in the heel tabs will be disposed 35 on the inside of the stocking and the reinforced areas in the leg portion above the topping line will appear at the heel corners as reinforced areas having a straight lower edge disposed at right angles to the topping line in the heel tabs in the finished stocking.

4. A stocking having its leg portion, heel tabs and foot portion of the same weight material throughout excepting the lower ends of the heel tabs and the toe portion and a few adjacent reinforced wales beginning a few courses above the 50 topping line and some of the wales extending past the topping line to the lower edge of the leg portion and the other adjacent reinforced wales extending along the proximate edges of the heel tabs, the remote reinforced wales of the heel tabs being loose wales so they can be topped at the same time the lower portion of the leg portion is topped, whereby when the foot portion is knitted the major portion of the reinforced wales will appear as a flap on the inside of the stocking and reinforced areas will be visible in the leg portion immediately above the topping line and at the junction of the leg portion, the heel tabs and the foot portion.

5. A full fashioned stocking having a leg portion, heel tabs and a foot portion, the lower end of the leg portion having a loose course and the heel tabs having each a loose wale spaced from their proximate edges, whereby a topping line is 65 formed for topping onto a footer, the leg portion, the tabs and the upper section of the foot portion being of single thread construction and having reinforced areas disposed immediately above the junction point of the loose wales with the loose courses and having reinforced wales along 70

the proximate edges of the heel tabs including the loose wales and having the extreme tips of the heel tabs reinforced, whereby when a topping operation is carried out the reinforced wales along the proximate edges of the heel tabs will lie on the inside surface of the stocking, and reinforced spots will be visible on the exterior surface of the stocking immediately above the heel corners and at the lower back portion of the heel.

6. A full fashioned stocking of the sheer type 10 having a loose course spaced from the lower end of the leg portion and having a loose wale disposed a few wales inwardly from the proximate

edges of the heel tabs and merging into the ends of the loose course, a few of the wales immediately above and inwardly of the ends of the loose course being reinforced, the loose wales and the few wales extending to the proximate edges being reinforced, whereby when a topping operation is carried out and the foot portion is knitted, the said few wales will appear on the inside surface of the stocking and a reinforced area will appear immediately above each heel corner.

JOHN P. MITZEL.
